TWO-STAGE STARTING SYSTEM FOR
INTERNAL-COMBUSTION ENGINESAnthony Miller, Elmira, N. Y., assignor to Bendix
Aviation Corporation, South Bend, Ind., a cor-
poration of Delaware

Application June 3, 1942, Serial No. 445,577

4 Claims. (Cl. 290—38)

The present invention relates to a two stage starting system for internal combustion engines and more particularly to such a system incorporating an automatic delayed action switch for controlling the application of full battery voltage to the starting motor.

Various forms of two stage starter controls have been heretofore used for delaying the full energization of the starting motor until after the driving connection to the engine has been established. Their use, however, has been limited to some extent by price considerations and by the factor of undesirable complications.

It is an object of the present invention to provide a novel two stage engine starting system which is efficient and reliable in operation while being simple and economical in construction.

It is another object to provide such a device incorporating a novel form of delayed action switch.

It is another object to provide such a device in which the delayed action of the switch is inherent in its construction and is substantially independent of the functional condition of the starting system.

Further objects and advantages will be apparent from the following description taken in connection with the accompanying drawing, in which:

Fig. 1 is a semi-diagrammatical illustration of a preferred embodiment of the invention showing the structure of the switch partly in side elevation and partly in vertical section;

Fig. 2 is a similar view showing the parts in the positions assumed immediately after closure of the starting switch; and

Fig. 3 is a similar view showing the parts in the positions assumed when the delayed action switch is closed and the starting motor fully energized.

In Fig. 1 of the drawing there is illustrated a starting system comprising a battery 1 grounded at 2 and connected by a lead 3 to a starting switch 4. A lead 5 connects the starting switch to one end of a resistor 6, the opposite end of which is connected by a lead 7 to the starting motor SM which is grounded at 8 to complete the starting circuit. The resistor 6 is of such value as to reduce the voltage of the battery as initially applied to the starting motor to a value which causes the initial engagement of the starting mechanism to take place without unnecessary shock.

Means are provided for bridging the resistor 6 to apply the full battery voltage to the start-

ing motor for cranking purposes. For this purpose fixed contacts 9 and 11 are connected to the opposite ends of the resistor 6 and a bridging contact 12 is mounted on a magnetic switch plunger 13, in position to cooperate therewith.

According to the present invention means are provided for actuating the switch plunger 13 to close the switch 9, 12, 11 a predetermined time after closure of the starting switch 4. As here shown, this means comprises a solenoid 14 connected by a lead 15 to the starting motor lead 5, and grounded at 16 so as to be energized from the battery 1 when the starting switch is closed. Solenoid 14 is provided with a bearing sleeve 17 of non-magnetic material extending substantially beyond the ends of the solenoid. The magnetic switch plunger 13 is slidably mounted in one end of the solenoid 14 within the bearing sleeve 17. Plunger 13 is considerably smaller in diameter than the interior of sleeve 17, and a bushing 18 of non-magnetic material is mounted on the plunger to slide freely in the sleeve and thus guide the plunger therein. A spring 19 is arranged to yieldingly oppose induction of the plunger into the solenoid.

A second plunger of magnetic material 21 is slidably mounted in the opposite end of the sleeve 17, adjacent the end of the solenoid 14 but not projecting within the solenoid to any substantial degree. This plunger is substantially larger in diameter than the switch plunger 13, so as to fit slidably within the sleeve 17, and a spring 22 is provided for normally maintaining the plunger 21 in the position shown in Fig. 1 against a stop 23. Separation of the plungers 13 and 21 is limited by suitable means such as a stem 24 which may be of non-magnetic material sweated or threaded into the switch plunger as shown at 24, slidably traversing an axial opening in the plunger 21 and having a stop shoulder 25 at its outer end.

In operation, closure of the starting switch 4 energizes the starting motor with reduced voltage due to the resistor 6, and at the same time energizes solenoid 14 of the bridging switch. Since the switch plunger 13 extends within the solenoid, energization thereof causes induction of the switch plunger until it strikes against the end of the plunger 21 as shown in Fig. 2, thus moving the bridging contact 12 away from the switch contacts 9 and 11. When the switch plunger 13 thus engages the large plunger 21, the flux of the solenoid 14 is caused to traverse the large plunger and draw it into the coil, thus projecting the

switch plunger to cause closure of the bridging switch as shown in Fig. 3. During this stage of the operation, the two plungers act as a single magnetic plunger of stepped diameter, the portion of large diameter being dominant in its effort to center itself in the solenoid 14, thereby effectively holding the bridging switch closed as long as the starting switch 4 remains closed.

In order to secure substantially uniform contact pressure in the switch, the contact 12 is preferably mounted slidably on the end of the switch plunger 18 and insulated from the plunger by means of a collar 26, while a spring 28 is provided for urging the contact against a terminal shoulder 27 on the switch plunger.

It will be appreciated that the time consumed by the plunger 18 in moving into the solenoid until it engages the plunger 21, stopping, and then being projected from the coil by the plunger 21, provides a delay which is quite uniform and sufficient to ensure engagement of the starting mechanism prior to full application of the battery voltage to the starting motor. Moreover, this delayed action is secured without the necessity of special design of the solenoid involving extra amounts of conductive materials.

Although but one embodiment of the invention has been shown and described in detail, it will be understood that other embodiments are possible and that various changes may be made in the design and arrangement of the parts without departing from the spirit of the invention as defined in the claims appended hereto.

What is claimed is:

1. In a two stage starting system for internal combustion engines a starting circuit including a resistor for reducing the initial flow of current therethrough and an electromagnetic switch for bridging said resistor, said switch including a contact member and a two part movable plunger,

one of the parts of said plunger being arranged to actuate the contact member; and means whereby initial energization of the switch causes said one part of the plunger to move into engagement with the other said part while moving the contact member away from closed position, after which the two parts of the plunger unite and move together to close the switch.

2. In an engine starting system a starting circuit including a starting motor and a resistor for reducing the initial energization thereof, a magnetic switch for bridging the resistor including normally open contacts, a solenoid, a magnetic plunger of small diameter controlling said contacts slidably mounted within one end of the solenoid, a magnetic plunger of larger diameter slidably mounted adjacent the opposite end of the solenoid, and means for simultaneously energizing the starting motor and said solenoid, said contacts being arranged to be closed by the projection of the small plunger from the solenoid by the larger plunger.

3. A delayed action electromagnet including a solenoid and a plunger formed in two coaxial parts, one part of large diameter located normally outside the effective zone of influence of the solenoid and the other part of smaller diameter normally spaced therefrom and movable by energization of the solenoid into engagement therewith whereby the magnetic flux of the solenoid is conducted by the part of smaller diameter through said part of large diameter and the solenoid is thereby made effective to actuate the part of large diameter.

4. A delayed action electromagnet as set forth in claim 3 including further means attached to one of said parts of the plunger and engageable with the other part thereof to limit separation of said parts.
